ARTICULATED TENDER.

Application filed April 1, 1927. Serial No. 180,201.

One object of our invention is to increase the capacity of a locomotive tender by making the tender in two parts connected by an articulated joint and supported upon three trucks, the central truck being located at the point between the two parts and carrying the articulated joint.

A further object of the invention is to make the articulated joint in such manner that the two sections of the joint will rest upon a centre bearing plate of the central truck, the parts being so arranged that the rear part of the tender can be jacked-up so that the section of the joint carried by said part will clear the other part, and the centre bearing plate of the truck, as well as the locomotive with the forward part of the tender mounted on two trucks, can be moved away from the jacked-up rear part.

The invention also relates to other details of construction described hereinafter.

In the accompanying drawings:

Fig. 1 is a side view of our improved articulated locomotive tender, showing the trucks in outline;

Fig. 2 is a plan view;

Fig. 3 is a plan view of the articulated joint;

Fig. 4 is a transverse sectional view of the joint on the line 4—4, Fig. 3;

Fig. 5 is a longitudinal sectional view on the line 5—5, Fig. 3;

Fig. 6 is a longitudinal sectional view on the line 6—6, Fig. 3;

Fig. 7 is a sectional plan view on the line 7—7, Fig. 5; and

Fig. 8 is a sectional plan view on the line 8—8, Fig. 1, showing the flexible enclosing side plates between the two parts of the tender.

Referring to Figs. 1 and 2, 1 is the front part of the locomotive tender, and 2 is the rear part, both parts being substantially the same length in the present instance. The front part of the tender not only has the usual water space but also has the fuel space shown at 3. The part 1 has a cylindrical filling opening 4 closed by a suitable cover, and the part 2 has an elongated filling opening 5 closed by an elongated cover.

The front part in the present instance has a fixed enclosing side plate 6 at each side, and the rear part 2 has a hinged side plate 7 at each side which rests back of the plate

6 as shown in Fig. 8. The plates 7 are held yieldingly against the plates 6 by springs 8 which are mounted on telescopic rods 9 pivoted to the end of the rear part of the tender and to the plates 7, so that when the tender is passing around a curve, the plates 7 will yield, but at all times closing the space between the two parts of the tender. Hinged to one part is a bridge plate 10, the free end of which rests upon the other part as shown in Fig. 1.

The tender is mounted upon three trucks, the wheel base of the centre truck being longer than those of the end trucks. In the present instance, the end trucks 11—11^a are four-wheel trucks of any approved design, while the central truck 12 is a six-wheel truck having a centre bearing plate 13, this plate being mounted on the truck bolster 14 in the usual manner. The centre plate has a depending flange 15 which extends over each side of the bolster, and has an annular flange 16 projecting upwards, forming a recess in which are located the two sections 17 and 18 of the articulated joint, the sections resting upon the centre plate within the flange 16 as shown in Figs. 4 and 5.

The section 17, which is attached to the forward part of the tender, is in the form of a ring 19, and extending from the base of the ring is an inner flange 20 and an outer flange 21. The flanges terminate in ribs which extend to the front plate 22 of the section 17. This front plate extends across the end of the body portion 23 of the front section of the tender. At the back of the ring 19 are diagonal ribs which extend to and brace the plate 24 which extends under the end of the body portion as shown in Fig. 5, making a very substantial coupling member of the joint that fits within the flange of the truck centre plate.

The section 18 of the joint has an end plate 25 which extends across the body portion 26 of the rear section of the tender, and a plate 27 which extends under the body portion 26 as shown in Fig. 5. These two portions 25 and 27 of the section 18 form a substantial support for the pin portion 28. This pin portion fits within the ring portion 19 of the section 17 and has a deep flange 29 which extends to the end plate 25, while at the rear of the pin section are diagonal ribs which extend to the plate 27.

Within the pin portion 28 are reinforcing ribs 30. The pin section, the centre plate, and the bolster of the truck each has a hole for the detachable pivot pin 31 having a head 5 that rests upon the pin portion 28.

By this construction, both sections of the coupling are free to turn on the centre plate of the central truck, and the pin portion 28 of the rear section of the joint is free to turn 10 within the ring portion 19 of the front section of the joint.

The two front plates 22 and 25 extend a considerable distance beyond the coupling at each side as shown in Figs. 3 and 4, forming 15 the supports for the side bearing brackets 32 and 33, respectively. These brackets have foot plates 34 and 35 which rest upon the side bearing plates 36 carried by the bolster 12. In the present instance, 20 the side bearing plates are integral with the bolster.

Each foot plate is preferably provided with a hard metal wear plate 37 and the side bearing plates with wear plates 38. The side 25 bearing plates 36 are flanged as at 39 and are each divided into two sections by a rib 40. The wear plates 38 are shaped to fit within the spaces enclosed by the flanges and ribs, each foot plate being directly above 30 an individual side bearing wear plate.

The tanks of the two parts 1 and 2 of the tender are connected by a coupling hose 41. This hose is attached to valve casings 42 as 35 shown in Fig. 1. These valve casings communicate with the bottom of each tank, and the valves in the casings can be readily opened or closed as desired.

By the above construction, the capacity 40 of the locomotive tender is greatly increased, and being made in two parts with an articulated joint, the tender will pass around ordinary curves. And by mounting the tender on three trucks, and locating the joint upon the central truck which has an extended 45 wheel base, a very substantial joint is made. Furthermore, by locating the joint member of the rear part of the tender within the joint member of the front part, the rear part can be jacked-up and the front part removed 50 with the locomotive, the central truck supporting the rear of the forward part.

By flanging the side bearing plates 36 as shown, the foot plates rest in the pockets formed by the flanges. The flanges prevent 55 any excess movement of the two sections of the tender, should the pin section 18 of the joint break or become defective.

We claim:—

1. The combination in a locomotive tender 60 made in two parts; means for connecting the water compartments of the two parts; three trucks located under the tender; and an articulated joint between the two parts resting upon the central truck.

2. The combination in a locomotive tender 65

made in two parts; means for connecting the water compartments of the two parts; three trucks located under the tender, the central truck being located at the joint between the two parts of the tender, and having a centre 70 plate; and a section of an articulated joint mounted on each part, the sections being connected and resting upon the centre plate of the central truck.

3. The combination in a locomotive tender, 75 of two parts, each part having a water compartment; a flexible hose coupling connecting the two parts; a hand-operated valve at each part; an articulated joint made in two sections, one section located within the other 80 section; and trucks upon which the tender is mounted, the central truck having a centre plate upon which the two sections of the joint rest, the rear section of the joint being capable of being detached from the forward 85 section and the central truck.

4. The combination in an articulated car, 90 of two parts; an articulated joint made in two sections, one section being attached to one part and the other section being attached 95 to the other part, one of said sections being in the form of a ring having an open centre, and the other section having a pin portion located within the ring portion of the other section; and a truck having a centre bearing 100 plate upon which the two portions of the joint rest.

5. The combination in an articulated car, 105 of two parts; an articulated joint made in two sections, one section being attached to one part and the other section being attached to the other part, one of said sections being in the form of a ring having an open centre, and the other section having a pin portion located within the ring portion of the other 110 section; and a truck having a centre bearing plate upon which the two portions of the joint rest, said plate having an annular flange encircling the ring section of the coupling.

6. The combination in an articulated car, 115 of two parts; an articulated joint coupling the two parts, said joint being made in two sections, one section located within the other; trucks upon which the car is mounted, the central truck being at the joint between the two sections and having a bolster; and a flanged centre plate on the bolster upon which the two sections of the articulated joint rest.

7. The combination in an articulated car, 120 of two parts; an articulated joint coupling the two parts, said joint being made in two sections, one section located within the other; trucks upon which the car is mounted, the central truck being at the joint between the two sections and having a bolster; a flanged centre plate on the bolster upon which the two sections of the articulated joint rest; and a detachable pivot pin ex- 125 130

tending through openings in one section of the joint and through openings in the centre plate and bolster.

8. The combination of a coupling connecting two sections of a car, one part having a ring section with an open centre, and the other part being in the form of a pin fitting the opening in the ring of the other section; a truck having a bolster; and a flanged centre plate on the bolster upon which both sections of the joint rest, the ring section of the joint having its bearing against the flange of the centre plate.

9. The combination of two parts of a car; an articulated joint coupling the two parts, each section of the joint having a plate extending across the end of one part of the car, one of said plates having a ring section and a foot plate at each side of the ring section, the other plate having a pin section and a foot plate on each side of said pin section, the pin section being located within the ring section; a truck having a bolster; a flanged centre plate mounted on the bolster

and forming a support for both the ring section and the pin section of the joint; and a side bearing at each side of the centre plate located under each foot plate.

10. The combination in an articulated car, of two parts; a coupling member on each part; a truck having a bolster on which the coupling members rest, said bolster having flanged side bearing plates; and foot plates projecting from the two parts of the articulated car and resting upon the side bearing plates within the flanges.

11. The combination in an articulated car, of two parts, each part having a coupling member; a truck having a bolster; a flanged centre on the truck supporting the coupling members of the two parts, said bolster having flanged side bearing plates; and a foot plate on each part on each side of the coupling and located within the flanges of the side bearing plates.
